DESIGN FOR A DESK CALENDAR SUPPORT OR THE LIKE

Joshua Gordon Lippincott, Scarsdale, N. Y., as-
signor to Keith Clark, Incorporated, New York,
N. Y.

Application March 1, 1940, Serial No. 90,619

Term of patent 7 years

To all whom it may concern:

Be it known that I, Joshua Gordon Lippincott, a citizen of the United States and a resident of Scarsdale, in the county of Westchester and State of New York, have invented a new, original, and ornamental Design for a Desk Calendar Support or the like, of which the following is a specification, reference being had to the accompanying drawing, forming a part thereof.

Fig. 1 is a plan view of a desk calendar support showing my new design;

Fig. 2 is a side elevational view;
Fig. 3 is a front elevational view; and
Fig. 4 is a rear elevational view thereof, a portion being broken away for convenience of illustration.

I claim:

The ornamental design for a desk calendar support or the like, substantially as shown.

JOSHUA GORDON LIPPINCOTT.
